UNITED STATES PATENT OFFICE.

SVEND E. JOHANNESEN, OF PITTSFIELD, MASSACHUSETTS, ASSIGNOR TO GENERAL ELECTRIC COMPANY, A CORPORATION OF NEW YORK.

HIGH-VOLTAGE TRANSFORMER.

1,337,915.

Specification of Letters Patent.

Patented Apr. 20, 1920.

Application filed July 15, 1918. Serial No. 244,836.

To all whom it may concern:

Be it known that I, SVEND E. JOHANNESEN, a citizen of the United States, residing at Pittsfield, county of Berkshire, State 5 of Massachusetts, have invented certain new and useful Improvements in High-Voltage Transformers, of which the following is a specification.

My invention relates to transformers, 10 some reactances, and like electrical apparatus and has for its objects an improved construction and arrangement of parts whereby such apparatus may be more economically manufactured.

15 My invention is particularly applicable to shell-type transformers but may also be applied to core-type transformers and is designed to afford a more efficacious manner of constructing, mounting and ventilating 20 the windings than has heretofore been known.

In shell-type transformers, as heretofore generally constructed, the coiled conductors comprising the windings were supported in 25 press-board casings which were in turn supported by the core; the assembled core when clamped together being anchored to a suitable base. In this construction barriers of insulating material were necessarily inserted 30 between the coils to provide the necessary resistance to puncture, creepage, etc. Such barriers, however, reduced the ventilating passages and consequently the full-load capacity of the transformer, the alternative construction being an increase in the 35 winding space with a corresponding decrease in the space-factor, together with an increased tendency for the windings to sag.

In the practice of my invention these 40 difficulties are avoided by reason of my novel construction of the coils, in which both adequate insulation and ventilation are provided without the use of barriers, the windings being supported independently 45 of the core.

In my new construction, the windings are so arranged that the potential drop between 50 portions of the windings is relatively small so that little insulation is needed between turns and such portions. As a consequence I insulate the windings in groups, a plurality of associated groups preferably being incased together in an insulating jacket of high dielectric strength; such jacket being formed to admit a free circulation of the

cooling medium between the groups over the edge of the conductors in the winding.

For a more complete understanding of the nature and objects of my invention, reference should be had to the accompanying 60 drawing in which Figure 1 is a perspective view showing the core and coils of a transformer embodying my invention in assembled relation; Fig. 2 is a vertical section through the transformer in the plane of 65 the coils, the lower part being broken away; Figs. 3, 4 and 5 are fragmentary sections taken on the lines 3-3, 4-4 and 5-5 respectively in Fig. 2; Figs. 6 and 7 are detailed views showing the manner of connecting the leading-in conductors to the 70 windings; Figs. 8, 9 and 10, show, in diagrammatic fashion, different schemes for arranging the coil groups in transformer windings constructed in accordance with 75 my invention; Fig. 11 is a top plan view of the arrangement of windings shown in Fig. 1, while Fig. 12 shows a plan view of a modified arrangement; Fig. 13 shows a core-type transformer partly in elevation and 80 partly in section, which has a cylindrical winding embodying my invention; and Fig. 14 is a section taken on the line 7-7 in Fig. 13.

Referring now to the drawings, and to 85 Fig. 1 in particular, 10 represents the core of laminated magnetic material suitable for a shell-type transformer, in the windows of which core are secured the coils 11 which are protected from the core laminations by 90 the insulating boxing 12. The boxing 12 is spaced both from the windings and the core as indicated in Fig. 2 in order to provide inner and outer ventilating passages 13 and 14 respectively. 95

I will now describe in detail the structure of coils 11 which are supported in position, not by the core, but by bolts 15 which are passed through a suitable insulating structure in the corners of each of the coils and 100 are made fast in the frame or casing (not shown) which supports the core 10.

The coiled electrical conductors 16 (see Fig. 3) which compose the coils 11 are wound in groups *a*, *b*, *c*, *d*, each group being 105 composed of a convenient number of turns. The conductors 16 are preferably copper strap which is covered by one or more coverings of cotton, silk or other insulating material; the groups when formed being var- 110

nished or otherwise treated to render them impervious to water and moisture.

The groups *a*, *b*, *c*, *d*, are assembled in concentric relation in a plane, the spaces between the groups being maintained by a plurality of cylindrical insulators 17 formed with reduced ends as clearly indicated in Fig. 3.

At the inner and outer edges of an assembled group *a*, *b*, *c*, *d*, I employ an insulating member 18 with rounded edges which serves not only to determine the contour of the finished coil but also as a base through which the bolts 15 are passed.

A finished coil has a plurality of associated groups *a*, *b*, *c*, *d* and *a'*, *b'*, *c'*, *d'*, assembled in spaced relation in two planes, one on each side of the insulating spacers 17 and 18, the whole being enveloped with a plurality of layers of insulating material 19, such material preferably consisting of fuller board taped back with cheese cloth where very high voltages are used, and muslin for the lower voltages, the whole being varnished and treated to form a substantially solid insulating jacket.

In order to provide ventilation for the interior of a coil constructed in this manner, I cut comparatively unrestricted slots, such as shown at 20, in both the top and bottom edges of the insulating jacket.

The bolts 15, which support the coils, must also be well insulated and are preferably themselves constructed of insulating material, the substance known to the trade as "micarta" answering well this purpose. The proper spacing of the coils 11 along the bolts 15 is insured by insulating sleeves or bushings 21 which are slipped over the bolts 15 but abut against the coil structure as shown in Fig. 4, the whole being secured by suitable nuts 22 which engage with the threaded extremities of the bolts 15.

The electrical connections between groups *a*, *b*, *c*, *d*, etc., in the interior of a coil are made in such a manner as to occasion the least possible strain on the insulation, one mode being shown in Figs. 6 and 7 and diagrammatically shown in Fig. 8, alternative modes being shown in Figs. 9 and 10.

In order that the connections shown in Fig. 6 may be more clearly understood, I shall assume that the left-hand and associated right-hand groups *a*, *b*, *c*, *d* and *a'*, *b'*, *c'*, *d'* respectively compose a coil across whose terminals 40,000 volts is to be impressed. Consequently there must be a difference in potential of 5000 volts across the conductors of each of the eight groups. To diminish the electrostatic strain in the intervening dielectric for the groups, I connect the last turn in group *a* to the first turn in group *a'*, its last turn being connected to the first turn in group *b* and so on until we come to the last turn of group

d'. From the first turn of group *a* to the last turn of group *d'*, there is to be a difference in potential of 40,000 volts, to which turns the leading-in taps 25 and 26 are connected. This arrangement is convenient because the difference in potential between the first and last turns of any two groups is only 5000 volts; that is, between the first turn of *a* and the first turn of *a'* there is 5000 volts, and between the last turn of *a* and the first turn of *b* there is 5000 volts and so on. By this arrangement the lead 25 does not pass adjacent any conductor of a greater potential difference than 5000 volts so that its insulation is a comparatively simple matter; while the other lead 26 which connects with the innermost turn of group *d'* is led straight out through the coil as shown, or it may be led over the outside and may readily be insulated as heavily as desired, especially adjacent the conductors in groups *a* and *a'*. These connections for the groups *a*, *a'*, *b*, *b'*, etc., and the manner of connecting the leads 25 and 26 are indicated in Fig. 8.

An arrangement in which the relative arrangement of groups *b*, *b'* and *c*, *c'* has been interchanged is shown in Fig. 9, while Fig. 10 shows an arrangement in which the groups *a''*, *b''*, *c''*, *d''*, which correspond to group *a'*, *b'*, *c'*, *d'* in Fig. 8, are connected in inverted order; that is, the turns progress from inside outward instead of from outside inward. Still other arrangements will occur to those skilled in the art.

The primary and secondary coils for my improved transformer are constructed substantially similar, as above described except that the size and number of conductors in each group comprising a coil 11 is determined by the ratio of transformation.

In an assembled transformer the primary and secondary coils may be interleaved as indicated at P and S in Fig. 11, or all the coils 11 of either kind may be grouped together. This latter arrangement is of particular advantage for the high voltage coils, which group as a whole may be enshrouded in an insulating jacket shown at 27 in Fig. 12.

The jacket 27, in this instance, is not only provided at top and bottom with slots registering with slots 20 in coils 11 to admit the circulation of a cooling and ventilating medium to the interior of coils 11, but is provided in addition with slots 28 at top and bottom admitting the cooling and ventilating medium to the spaces between the coils 11.

A shell-type transformer, constructed in this manner, is very rugged and requires a smaller number of parts than has heretofore been used in their construction, the jacket of fuller board and cheese cloth providing adequate insulation for the wind-

ings from each other and from ground, where very high voltages are used, a jacket of muslin, treated and varnished being sufficient for the lower voltages. The provision of openings 20 at the top and bottom of each coil, for admitting the cooling and ventilating medium (which may be oil, air, or other medium) to pass freely over one entire surface of an assembled winding, insures a rapid and uniform dissipation of the heat from the winding.

While I have shown and described my invention in the above as applied to shell-type transformers, it is by no means confined to this type for I have contemplated using it in connection with core-type transformers using any suitable known type of winding; one embodiment thereof being shown in Figs. 13 and 14 which I will now describe.

In these figures, 30 denotes a core having a cylindrical coil 31 surrounding and suitably spaced from one leg of the core 30.

The coil 31 comprises inner and outer superimposed concentric groups of coiled conductors e, e', f, f' , etc. Radial spacers, such as shown at 32, are preferably arranged in superimposed staggered relation to insure the proper spacing of the groups. The assembled groups have annular end spaces 32 formed to give a rounded edge to the cylindrical coil, the whole being secured together by the insulating jacket 33. The jacket 33 has openings 35 cut in its top and bottom edges so that the cooling and ventilating medium is freely admitted to the space between the concentric groups of coiled conductors, passing over one entire cylindrical surface of each winding to quickly absorb and dissipate the heat from each winding.

A completely assembled transformer, such as I have shown in Fig. 13, would have one or more suitably connected cylindrical coils 31 surrounding each leg thereof.

Having now described what is at present the best means known to me for carrying out an embodiment of my invention, I would have it understood that such means are merely illustrative and that I do not mean to be limited thereby to the exact details shown nor in the choice of recognized equivalents except as defined in my claims hereunto appended.

What I claim as new and desire to secure by Letters Patent of the United States, is,—

1. In a transformer, the combination with a core, of a coil comprising a plurality of associated groups of coiled conductors, insulating spacers for maintaining said groups in a predetermined spaced relation and an insulating jacket enveloping said groups, said jacket being provided with unrestricted openings for admitting a cooling and ventilating medium to circulate be-

tween said groups and over the edges of said conductors.

2. In a transformer, the combination with a core, of a coil comprising a plurality of associated groups of coiled conductors, insulating spacers for maintaining said groups in a predetermined spaced relation, the spacers at the bounding edges of said groups being shaped to give the coil a desired contour, and an insulating jacket enveloping said groups, said jacket being provided with unrestricted openings for admitting a cooling and ventilating medium to circulate between said groups and over the edges of said conductors.

3. In a transformer, the combination with a core, of a coil comprising a plurality of associated groups of coiled conductors, insulating spacers for maintaining said groups in a predetermined spaced relation, the spacers at the bounding edges of groups being shaped to give the coil rounded edges, coil supporting bolts passing through the edge spacers, and an insulating jacket enveloping said groups, said jacket being provided with unrestricted openings for admitting a cooling and ventilating medium to circulate between said groups and over the edges of said conductors.

4. In a transformer, the combination with a core, of a coil comprising a plurality of associated groups of coiled conductors, insulating spacers for maintaining said groups in a predetermined spaced relation, said groups having electrical connections between end turns so arranged that the potential difference between adjacent portions of said groups is not greater than a predetermined fraction of the potential difference across the coil's terminals, and an insulating jacket enveloping said groups provided with unrestricted ventilating openings.

5. In a transformer, the combination with a core, of a coil comprising a plurality of associated groups of coiled conductors, insulating spacers for maintaining said groups in a predetermined spaced relation, terminals for said coil, one being connected in series with an outermost turn of the connected groups, the other being connected to an innermost turn and led straight out of the coil traversing the space between said groups, and an insulating jacket enveloping said groups provided with unrestricted ventilating openings.

6. In a transformer, the combination with a shell type core, of a coil structure composed of a plurality of units comprising windings and an insulating structure, supporting bolts passing through said coil structure, and means for securing said coil units along said bolts in predetermined spaced relation.

7. In a transformer, the combination with

- a shell type core, of a coil structure composed of a plurality of units comprising windings and an insulating structure, supporting bolts passing through said coil structure, insulating sleeves on said bolts between and abutting said coil units, and nuts engaging with the extremities of said bolts to hold said coils in predetermined positions along said bolts.
8. In a transformer, the combination with a shell-type core of laminated magnetic material, of a plurality of coils passing through the windows thereof, said coils comprising associated groups of conductors concentrically arranged in planes spaced apart and having insulating spacers about the edges thereof, supporting bolts passing through the spacers on the outside edge of said coils, and means for securing said coils along said bolts in a predetermined spaced relation.
9. In a transformer, the combination with a core of laminated magnetic material, of a plurality of coils passing through the windows thereof, said coils comprising associated groups of conductors concentrically arranged in planes spaced apart and having insulating spacers about the edges thereof, supporting bolts passing through said spacers, an insulating jacket enveloping each coil and provided with unrestricted ventilating openings, and means for securing said coils along said bolts in a predetermined spaced relation.
10. In a transformer, the combination with a core of laminated magnetic material, of a plurality of coils passing through the windows thereof, said coils comprising associated groups of conductors concentrically arranged in planes spaced apart and having insulating spacers about the edges thereof, means for securing said coils along said bolts in a predetermined spaced relation, 40 and an insulating jacket enveloping each coil and provided with unrestricted ventilating openings and an additional insulating jacket enveloping a group of coils having ventilating openings in register with the first mentioned openings and additional openings communicating with the spaces between said coils.
11. In a transformer, the combination with a core of laminated magnetic material, of coils composed of associated groups of coiled conductors arranged concentrically in planes in spaced relation, and an insulating jacket for each coil provided with openings in the top and bottom edges.
12. In a transformer, the combination with a core of laminated magnetic material, 60 of coils composed of associated groups of coiled conductors arranged concentrically in planes in spaced relation, supporting bolts passing through said coils, means for securing said coils along said bolts in a predetermined spaced relation, an insulating jacket for each coil provided with openings in the top and bottom edges, and an additional jacket enveloping a group of coils having openings in register with the first 65 said openings and additional openings communicating with the spaces between said coils.
10. In a transformer, the combination with a core of laminated magnetic material, of a plurality of coils passing through the windows thereof, said coils comprising asso- 70

In witness whereof, I have hereunto set my hand this 8th day of July, 1918.

SVEND E. JOHANNESEN.
